UNITED STATES PATENT OFFICE.

JOHN HEOTES, OF TOMAHAWK, WISCONSIN.

SLIDING DRAWER AND LOCKING MEANS THEREFOR.

Application filed April 12, 1922. Serial No. 552,003.

To all whom it may concern:

Be it known that I, JOHN HEOTES, a citizen of the United States, residing at Tomahawk, in the county of Lincoln and State 5 of Wisconsin, have invented new and useful Improvements in Sliding Drawers and Locking Means Therefor, of which the following is a specification.

This invention has reference to an article 10 of furniture.

The object of the invention is to produce an article of furniture having sliding drawers that shall be provided with means for preventing the opening of the drawers except by authorized persons.

A further object is to produce an article 20 of furniture provided with a sliding drawer that is divided into a front and into rear compartments, spring influenced means being arranged on the bottom of the drawer to contact with the outer member of the frame of the furniture to prevent the opening of the drawer, said spring influenced means being effectively concealed but designed to 30 be contacted by a suitable instrument to permit of the opening of the drawer, spring means being employed to influence the drawer to open position, and wherein, after the first mentioned locking means have been 35 released, the remaining locking means will be brought to contacting engagement with the frame so that only the outer compartment of the drawer will be open, a similar instrument being necessary to depress the remaining spring influenced means to permit access being obtained to the inner compartments of the drawer.

The foregoing, and other objects which 40 will present themselves as the nature of the invention is better understood, may be accomplished by a construction and combination of parts such as is disclosed by the drawings which accompany and which form part of this specification.

45 In the drawings:—

Figure 1 is a vertical transverse sectional view through an article of furniture such as a cabinet in accordance with this invention.

Figure 2 is a bottom plan view thereof, 50 the legs of the cabinet being in section.

Figure 3 is a sectional view approximately on the line 3—3 of Figure 2, but showing the drawer opened to permit access to the outer compartment thereof.

55 Figure 4 is a bottom plan view of the drawer.

Figure 5 is a top plan view thereof.

Figure 6 is a detail view.

A cabinet or similar article of furniture is illustrated by the drawings and is broadly indicated by the numeral 1. The cabinet may be provided with any desired number of secret drawers which are locked in accordance with this invention, only one of the same, however, being shown by the drawings. The outer face or frame for the drawer is indicated by the numeral 2, the drawer being broadly indicated by the numeral 3. The drawer slides through the frame on the usual cleats 4, the lower edges 60 of the sides of the drawer, in the present instance projecting a suitable distance below the bottom 5 thereof. Secured to the under face of the cleats 4 there is a bottom board for the cabinet 2 which is indicated by the numeral 6, and there is a slight space 65 provided between the outer edge of the board 6 and the lower member of the frame, the said lower member being, for distinction, indicated by the numeral 7. 70

Secured to the bottom 5 adjacent to the inner edge thereof there is a pair of stop members 9 respectively. The members 9 are constructed of some suitable springy material either wood or metal, and are each 75 in the nature of a flat bar. Each of the stop bars 9 has its upper face at its outer end beveled, as at 10, and securing means 11 pass through this end of the stop bars and enter the bottom of the drawer to hold 80 the opposite ends of the stop bars at a downward inclination and in the path of contact with the lower member 8 of the frame. By such arrangement, it will be seen that the drawer cannot be moved to 85 open position until after suitable flat elements are inserted in the space 7 and brought to contact with the said stop members to spring the same above the upper edge of the member 8 of the frame. 90

The drawer is divided by suitable partitions into an outer compartment 12 and inner compartments 13. For distinction, the partition that provides the rear wall of the outer compartment is indicated by the numeral 14, the confronting end walls of the inner compartments being spaced a suitable distance away from each other whereby a space is arranged therebetween at the rear of the drawer to accommodate a block 15 105 110 that is secured to the rear wall of the cabinet. The block has on its front face a coiled

spring 16, the said spring contacting with the rear wall of the partition 14 impedes the drawer to partial open position when the stop members 9 have been operated, as previously described.

It is one of the purposes of this invention to provide means whereby the inner compartments of the drawer are rendered secret even should a person have knowledge of operating the stops 9 to open the drawer to obtain access to the outer compartment 12, and to accomplish this I secure on the bottom 5 of the drawer 3, at the rear thereof, and centrally between the stop members 9 an additional but shorter stop 17. This stop may be constructed of wood or metal, but in the showing of the drawings is in the nature of an arched spring plate, the same having its rear end secured to the bottom 5 of the drawer at the rear thereof. The stop 17 is of a length equalling the distance between the rear of the drawer 3 and the outer face of the partition 14, and it will be apparent that when the drawer is opened, as previously described, the stop 17 will contact with the member 8 of the frame so that it will be necessary to insert a flat instrument through the space 7 to force the stop 17 out of contact with the member 8 of the frame before the drawer can be moved to a further outward position to obtain access to the rear or inner compartments 13.

It is believed that the foregoing description, when taken in connection with the drawings will fully set forth the construction, operation and advantages of the improvement to those skilled in the art to

which such inventions relate, and that further detailed description will not be required. It is thought necessary to state, 40 however, that I do not desire being restricted to the precise structural details herein set forth and that I may make any such changes therefrom as fall within the scope 45 of what I claim.

Having described the invention, I claim:—

The combination with a cabinet or similar article of furniture having a drawer opening, a drawer slideable through the opening, a bottom below the drawer whose outer edge 50 is spaced from the frame of the cabinet, said drawer divided into an outer and inner compartments, spring means in the cabinet contacting the drawer for influencing the same to open position, downwardly inclined spring 55 bars secured to the bottom of the drawer in contact with the outer member of the frame of the cabinet for holding the drawer from opening, and said members designed to be moved to releasing position by the insertion 60 of an instrument through the space between the bottom and frame of the cabinet to move the bars out of contact with the cabinet, and a downwardly inclined spring stop member 65 secured to the bottom of the drawer for contacting the frame of the cabinet when the drawer has been moved a distance to uncover the outer compartment, and wherein a flat instrument must be inserted in the referred to space to influence the last mentioned stop 70 to permit of the full opening of the drawer.

In testimony whereof I affix my signature.

JOHN HEOTES.
